UNITED STATES PATENT OFFICE

2,502,698

APPARATUS FOR DRAINING RAILROAD
REFRIGERATOR CARS

Harry K. Blanning, Chicago, Ill.

Application May 25, 1948, Serial No. 29,010

1 Claim. (Cl. 137—21)

1

This invention relates to improvements in apparatus for draining the coolant or brine tanks of railroad refrigerator cars, and particularly to a valve and valve operating mechanism for performing this function.

A principal object of this invention is to provide a valve and valve operating mechanism whereby the valve may be opened or closed by an operator positioned on the roof of a refrigerator car. The men performing such re-icing operation do so from the roof of the car where the ice bunker doors are located.

Often when cars are re-iced in transit, only a portion of the accumulated brine, sufficient to provide some space for additional ice, will be removed. With conventional devices it is necessary for two men to perform this operation, one man on the ground to operate the valve, and a second man on the roof of the car to observe the liquid level. Even if all the coolant is to be drained off, it is necessary that a man climb off and on the car from the roof where the re-icing is done to the ground where access to the valve can be obtained. Therefore, ability to operate such valves from the roof of the car saves the time and trouble which would otherwise be required for a worker to descend from the car each time the valve is to be opened or closed.

Further objects and advantages of the invention include: a valve, simple in operation, that has a minimum number of moving parts; a valve which is so constructed that there is no danger of the valve "freezing" from the action of brine on the parts thereof; a valve which will be unaffected by the cinders, dirt, and sludge which inevitably become lodged in the coolant tanks of a refrigerator car because of the conditions of service under which the car must operate; a valve which will provide a tight seal against the loss of coolant even after considerable wear has occurred as a result of continued use of the valve; a valve in which only a single part is subject to any amount of wear, and which part is inexpensive and may be readily replaced; a valve which may be locked or "sealed" in an open or closed position to prevent tampering therewith except at such times as it is necessary to change the setting of the valve during re-icing operations; and a valve which is constructed and positioned for maximum safety to railroad personnel working about the car.

Additional advantages and objects of the invention will become apparent as the disclosure proceeds, and the description is read in conjunction with the accompanying drawings, in which

2

Fig. 1 is an elevational section of the end of a refrigerator car, showing the coolant tanks and the valve formed integrally with the drain header for the tanks;

5 Fig. 2 is a section taken at line 2—2 of Fig. 1; Fig. 3 is a section taken at line 3—3 of Fig. 2; Fig. 4 is a section taken at line 4—4 of Fig. 2; Fig. 5 is a section of the "ball" used in the valve;

10 Fig. 6 is a view corresponding to that of Fig. 2, with the valve and operating mechanism positioned outside the end wall of the refrigerator car and constructed as a unit apart from the drain header;

15 Fig. 7 is a section of the valve shown in Fig. 6, with the portion above the "break" rotated at 90° from the assembled condition shown in Fig. 6; Fig. 8 is a perspective view of the guide cap for the valve shown in Figs. 6 and 7;

20 Fig. 9 is a transverse section of the operating rod of the valve taken at line 9—9 of Fig. 7; and Fig. 10 is a perspective view of the latch for the valve shown in Figs. 6 and 7.

The present application is a continuation in 25 part of my prior application, Serial No. 756,530, the disclosure of which is incorporated herein by reference, to the extent that it is not inconsistent herewith.

Fig. 1 is an elevation of the inside of the end 30 of a refrigerator car in which are installed four, spaced, brine tanks 16, 17, 18 and 19, each of which has a drain 21 communicating with a common drain header 22. The tanks are supported from the sides of the car by means of longitudinal channels 23 and angle irons 24. Blocks 26 support the header from the floor of the car and straps 27 maintain the header 22 in alignment under drains 21.

A hatch 28 in the roof of the car provides 35 access to tanks 16 and 17, which are open at the top so that the ice or other coolant may be inserted therein. Deflectors 29 prevent the coolant from being spilled about the sides of the tanks, and a channel 31 fitted over the adjacent sides of tanks 16 and 17 prevents the spill of the coolant between the tanks. Channel 31 is placed on the top of the tanks with the legs of the channel turned downwardly along the sides of the tanks, Fig. 1. Two end flanges 32 are provided on channel 31 and fit over the outside of the two ends of the tanks, as shown in Fig. 2, to assist in maintaining the position of the channel with respect to the tanks. The foregoing description of the hatch and related construction is duplicated for tanks 18 and 19.

Hatch 28 will be closed by means of a hinged cover, not shown, of conventional construction, and having means by which the hatch cover may be "sealed" in a closed position. Details of suitable hatch cover construction may be found in "Car Builder's Cyclopedias," 1946 edition, page 160 et seq.

Immediately below the space between tanks 16 and 17 a pipe flange 33 is welded to the top of drain header 22, and a second pipe flange 34 is welded to the bottom of the drain header. A pipe 36 forming a guide is attached to flange 33 by means of a bushing 37 and projects upwardly in the space between tanks 16 and 17. The upper end of guide 36 terminates and is held in an opening 38 in channel 31, as is shown in Fig. 3.

The details of the valve construction are best shown in Fig. 4. What may be termed a valve seat body 39 is threaded into bottom flange 34 and is formed with an internal, tapered, valve seat 41. The valve seat 41 has the shape of a frustum of a cone; and for the purpose of convenience I have designated this shape as frusto-conical.

Preferably the angle between opposite faces of the seat is approximately 40°. I have found that the use of an angle of 40° provides positive seating of the "ball" as hereinafter described, and yet the "ball" is not wedged so tightly in the seat that it cannot be removed therefrom. A further advantage of the use of this angle is that it is steeper than the angle of repose of any dirt, cinders, or other sediment that may become deposited in the tank, and thus such sediment will not become lodged on the face of the valve seat to impair operation of the valve.

The closure for the valve is made in the form of a "ball" 42, preferably made of gum composition rubber of approximately 40 durometer hardness. Using a "ball" 2 1/8 inches in diameter, the diameters of the conical valve seat 41, as measured across the parallel planes which define the frustum of the cone, may be 2 5/8 inches at the base of the frustum and 1 3/4 inches at the top of the frustum.

The "ball" is moved in and out of engagement with the valve seat by means of a lifter rod 43. As is seen in Fig. 5, the "ball" 42 is held on the lifter rod between dished compression washers 44 engaged between nuts 46 and 47 threaded onto rod 43. In attaching the "ball" it may be compressed out of shape to some extent by tightening nuts 46 and 47 toward each other, which resultant configuration may be referred to as semi-spherical. A lock nut 48 may be jammed up against nut 47 to prevent the latter from being jarred loose.

A handle 51 is attached to the upper end of rod 43 (Fig. 3), which handle is formed with downwardly turned legs 52 which are spaced so as to slip outside the side flanges of channel 31. When the "ball" is to be in seated position (Fig. 4), the legs 52 of handle 51 are placed parallel to the sides of channel 31, and the handle will then drop downwardly until the "ball" becomes seated, as is shown in full lines in Fig. 3. When the valve is to be opened, the handle 51 is lifted and rotated 90°, whereupon legs 52 of the handle will rest on the web of channel 31 to hold the valve open, which position is shown in dotted lines in Figs. 2 and 3.

Valve seat body 39 is extended below the frame of the car, as shown in Fig. 2, and is there provided with a hexagonal-shaped head 53 to facilitate gripping it with a wrench. A threaded por-

tion 54 is formed on the lower end of body 39 to receive a tail pipe 56 sufficiently long that the discharge from the brine tanks will be ejected at a point where it will not come into contact with the car body or running gear.

Figs. 6 through 10 inclusive are illustrative of a form of a valve used when it is to be installed outside the end of the car. Such an installation is of particular value where the valve is to be substituted for another on a previously constructed car. Where the refrigerator car is one that has been built some time ago, it would be laborious and expensive to replace the existing construction with the form of valve shown in Figs. 1 through 5 inclusive. However, by merely making the necessary connections to the line from the drain header it is a simple matter to install a valve embodying my invention outside the end of the car.

Fig. 6 again illustrates one of the four coolant tanks, the drains 21 of which are connected by a common drain header 22. A drain line 61 from the drain header is brought outside the end wall 62 of the refrigerator car where it terminates in a valve body, generally designated 63. Threaded into the bottom of valve body 63 is a valve seat body 64 having a frusto-conical valve seat 41, previously described. A tail pipe 56 is attached to the bottom of the valve seat body 64.

The upper end of the valve body 63 is extended to form a chamber 65, into which the "ball" 42 may be raised to permit a full flow of coolant throughout the valve. This is of value to facilitate the draining of the tanks as rapidly as possible when they are to be re-iced, with a resulting minimum amount of delay before additional ice may be added.

In the top wall of chamber 65 a bushing 67 is threaded into body 63, and a guide 68 is in turn threaded into the bushing. In the wall of valve body 63, diametrically opposite the end of pipe 61, is a threaded opening 69 through which a suitable implement may be inserted to clean out pipe 61. The opening is provided with a threaded plug 71 to normally prevent the flow of coolant through the opening 69.

A lifter rod 72 is inserted through guide 68 and has the lower end threaded for the mounting of "ball" 42 engaged between dished compression washers 44 by nuts 46, 47, and 48, as previously described. The upper end of lifter rod 72 is provided with a crosspiece 73 which serves as a handle for the operation of the valve. Along two sides of the upper end of lifter rod 72 and diametrically opposite each other are a pair of ribs 74, which serve both to strengthen the upper portion of the rod and also to align the rod and handle, as hereinafter described.

At the upper end of guide 68 is a cap 76, the end of which is provided with a circular, central, opening 77, which opening has two side notches 78 to accommodate ribs 74 of lifter rod 72. In attaching the cap 76 to the guide 68 the notches 78 are aligned normal to end 62 of the car in order that handle 73 will be positioned parallel to the end of the car by ribs 74. This positioning is of importance because it greatly diminishes the possibility of injury to railroad personnel working on or about the car, which might otherwise result from their bumping the projecting handle or catching it in portions of their wearing apparel.

The top face of the cap 76 has two pairs of raised lips 79 which will be parallel to the end

of the car when the cap is in place. When lifter rod 72 is raised to the extent that "ball" 42 is within opening 65 of valve body 63, the bottom of ribs 74 on the lifter rod will be slightly above the top of lips 79, which will allow the handle 73 to be rotated 90°. If the handle is now released, the ribs 74 will fit between lips 79 and rest on the upper face of cap 76. The lips serve to hold the handle in that position until it is desired to again close the valve, which may be accomplished by raising the handle so that the bottom of the ribs 74 are above the top of the lips 79, thus permitting the handle to again be rotated 90° so that the ribs will slip down through notches 78 in the cap.

A latch 81 is pivotally mounted by means of pin 82 to a bracket 83 clamped to guide 68 by means of a bolt 84. The latch is provided with a pair of spaced openings 86 and 87, and the lower opening 86 is adjusted so that the latch will just slip over one end of handle 73 when the "ball" 42 is seated in the valve seat 66, as is shown in full lines in Fig. 7. This adjustment may be obtained by loosening bolt 84 holding bracket 83 and sliding the bracket up or down guide 68 until the proper position is obtained, whereupon the bolt 84 may be re-tightened. As has been previously explained, the portion of Fig. 7 above the "break" has been rotated 90° from the actual position in Fig. 6 to better illustrate that portion of the valve mechanism.

If the handle 73 is raised so that it will slip into upper opening 87 in latch 81, as shown in dotted lines in Fig. 7, the valve will be positioned in a partially opened condition. It is often necessary during the winter months to leave the valve slightly open to assure that it will not freeze closed. The latch will hold the valve in this condition and eliminate tampering with it.

A transverse slot 88 is formed in one end of handle 73 to permit the insertion of a seal 89 after the handle has been latched in the closed or partially opened position. The ability to seal the valve in the desired position prevents tampering with the valve, except at such times as authorized personnel are desirous of changing the position thereof. The same result is achieved with the embodiment shown in Figs. 1-5 by sealing the hatch cover, which will prevent access

to handle 51 of the valve. When the car is to be re-iced, the authorized personnel may break the seal to change the position of the valve, if that is found to be necessary. After the re-icing procedure is completed or the valve reset, the latch may again be slipped over the handle at the desired position of the valve and a new seal inserted through opening 88 in the handle.

I claim:

- 10 For use in refrigerator cars having a plurality of brine tanks to which access is had through one or more hatchways in the roof of the car, and connected below the lowermost portions thereof by a drain header having relatively flat
- 15 top and bottom walls and located within the confines of the car body, the combination therewith of a drain valve for the header comprising a guide column located adjacent to one of said tanks and communicating at the top with one of said hatchways and at the bottom with the header through an opening in the top wall thereof, a fitting secured to the top wall of the header for supporting the lower end of said column over said top wall aperture, a second fitting secured
- 20 to the lower wall of the header about an aperture in said lower wall directly below the first opening, a tubular valve seat body detachably connected to said second fitting and having a frusto-conical valve seat, said body providing an open
- 25 passage from the header to the exterior of the car, a valve rod in the guide column having a handle projecting into the adjacent hatchway and carrying a resilient valve member at its lower end adapted to cooperate with said valve seat
- 30 35 to close said passage in the valve seat body when the valve rod is in its lowered position, and means for supporting said rod in its raised position.

HARRY K. BLANNING.
